V. J. MILLER

WATER ELEVATOR

Filed Feb. 13, 1922

UNITED STATES PATENT OFFICE.

VERNON J. MILLER, OF EAST ORANGE, NEW JERSEY.

WATER ELEVATOR.

Application filed February 13, 1922. Serial No. 536,134.

To all whom it may concern:

Be it known that I, VERNON J. MILLER, a citizen of the United States, residing at East Orange, in the county of Essex and State of New Jersey, have invented certain new and useful Improvements in Water Elevators, of which the following is a specification.

This invention relates to improvements in what may be termed water-elevators, especially of the piston-type, and is particularly designed for providing a source of water-supply for houses or dwellings in obtaining such supply from a well or cistern, where a source of water-supply is not available by the facilities provided in cities.

The invention has for its object, among other purposes, to provide for automatically controlling the delivery of the water-supply from the cistern or well to the dwelling or house.

A further object is to provide for simplifying and lessening the parts and to promote efficiency and carry out the aforesaid ends or purposes in an inexpensive and expeditious manner.

Other objects of the invention, together with the foregoing, will be apparent from the following description and accompanying drawing thereof.

The invention therefore consists of certain instrumentalities and features of construction substantially as hereinafter more fully disclosed and defined by the appended claim.

In the drawing is disclosed the preferred embodiment, or forms, of my invention, wherein it will be understood that various changes and modifications as relate to the detailed construction and arrangement of parts may be made without departing from the spirit or scope of the invention as covered by the claim, and in which drawings:

Figure 1 is a longitudinal section of my invention.

Fig. 2 is a similar view of a form of the same wherein the piston is provided with a valve, and the water-inlet pipe is provided with a valved extended inlet member or pipe delivering into the cylinder above the piston.

Fig. 3 is a like section of the invention, the outlet or house-feed-pipe being shown as having a second valved connection with the piston-cylinder.

Fig. 4 is a longitudinal section of a two-cylinder and two-piston type of the invention, and

Fig. 5 is a like sectional view of a horizontally arranged type of the invention.

Fig. 6 is a sectional fragmental view showing a slight modification of the previous figures in that the inlet valve 9 and the outlet valve 12 are arranged in the well pipe 7 and the outlet-pipe 11 respectively, the well-pipe connection in this instance being effected with the bottom of the cylinder and having connection by means of arms 6^a and 6^b with the outlet-pipe 11 and intake pipe 11^a, respectively, the intake pipe 11^a connecting at its upper end with the cylinder at the upper end, above the piston, the valve 9 being arranged in the well-pipe intermediate the connections of the two arms 6^a and 6^b of the well-pipe 7.

As characteristic features of my invention, I provide a cylinder 1, preferably bottomed, but which may be open or closed at the opposite end and within the cylinder is provided a piston 2 having a carrying rod 1^a. The piston carrying rod 1^a is weighted by suitably applying preferably heavy metallic members or weights 3 thereon, whereby the required pressure may be exerted upon the water or contents within the cylinder below the piston, as in forcing or delivering the water from the cylinder out through the outlet or house pipe, the water previously, of course, upon the piston-up-stroke, having been sucked into the cylinder and the intake pipe valve automatically closing, all as later seen. Suitable mechanical appliances are employed for raising or lifting the piston 2 after making its down-stroke, as for instance, a cable 4 wound upon a drum 5 adapted to be hand-actuated or otherwise, as indicated, these however, being only used as expedients and not constituting, as such, essentials of my invention, may be optionally exchanged for other suitable means, as will be appreciated.

A water-inlet or intake pipe 6 is supplied to the cylinder 1, laterally thereof and clear down, adjacent its bottom, or it may even enter the cylinder at the bottom, and to the inlet pipe 6 is supplied a well or cistern-entering pipe 7, at right-angles thereto, the connection between the cylinder and said pipes being effected by means of a right-angled hollow or tubular member 8, of el-

bow-like construction. The member 8 is provided with an inlet water pressure-controlled valve 9 adapted, when the cylinder is filled or supplied with water by suction 5 caused by the upstroke of the piston, to automatically cut off the outflow of the water from the cylinder via the inlet pipe 7.

An outlet or outtake-pipe 10 is supplied laterally to the cylinder 1, or it may even 10 enter the bottom thereof, or it may connect with the inlet-pipe intermediate the check-valve thereof and the cylinder, the check-valve in the outlet pipe being suitably arranged in a plane above the check-valve of the intake pipe. The outlet or outtake pipe 15 10 has supplied thereto a pipe 11 adapted to be led to a dwelling or house, or other point to which it may be desired to convey the water for convenience in use. The connection between the outtake or delivery pipe 20 and the pipe 11 is effected by means of a tubular or hollow right-angled, or elbow-like, member 12, which is provided with a water-pressure-controlled valve 13, adapted, 25 while the cylinder is being filled or supplied with the requisite quantity of water, as predetermined by the weighted piston, and during the down stroke of the piston, to automatically open up communication between 30 the cylinder 1 and the pipe 11 via the pipe 10 and for the delivery of the water from the cylinder, the valve 9 automatically closing under the water pressure in the cylinder.

In the form or modification of the invention as disclosed by Figure 2, I employ a piston 2^a having a downwardly opening valve 2^b, and provide the water-intake pipe with a valved pipe-extension 14, effecting connection with the cylinder at a point providing also for the delivery of water above the piston, the valve of the extension pipe 14 being indicated at 14^a, thus providing for supplying water into the cylinder both below and above the piston as shown.

In the form or modification, as disclosed by Fig. 3, I have shown the Fig. 1 form of my invention, as provided with the water-intake valved extension pipe 14 and its valve 14^a, also the outtake pipe 11 thereof 50 as having a valved connection 15 with the cylinder 1, adjacent the upper end of the cylinder.

This arrangement is double-acting. As the piston makes its down stroke the water 55 enters the outlet pipe, at the lower end of the cylinder, is thence drawn into the cylinder at its upper end, and, upon the upstroke of the piston the water is forced through the outlet pipe connection at the 60 upper end of the cylinder, and at the same time the cylinder is being filled from the pipe connected at the lower end. It does not matter whether the pipes, at the upper end, are connected thereto laterally or to its 65 top (the head), or angularly or otherwise,

the same arrangement or connection being also applicable to the bottom of the cylinder and the inlet pipe and the outlet pipe may enter the cylinder from the same pipe by means of a T provided with suitable valves. 70

In the form or modification as disclosed by Fig. 4, I have shown my invention as embracing a multiple of cylinders, with a common intake pipe 16 and a common outtake pipe 17, the intake-pipe having valved pipe connections in multiple form both at the upper and lower ends of each cylinder, as 18 and 19, respectively; also the outtake pipe having valved pipe connections, in multiple form, both at the upper and lower ends 80 of each cylinder, respectively, as at 21 and 20. This arrangement is a multiple of that shown in Fig. 3 except that the weights on the pistons are arranged to counter-balance each other. 85

In the modification or form of my invention as disclosed by Fig. 5, I have shown the same embracing the cylinder with its piston-rod extending from each side of the piston and adapted to be actuated from each 90 end, and by the actuating cable and drum or pulley, with the weight, as above shown, adapted to function with the parts arranged horizontally, the same otherwise being devised along the general lines of the form or 95 modification disclosed by Fig. 3.

As disclosed in the modification designated as Fig. 6 of the drawings, it will be observed that I have shown the inlet-valve 9 and outlet valve 12 as arranged in the 100 well pipe 7 and the outlet pipe 11, respectively, the well-pipe connection, in this instance, being effected with the bottom of the cylinder and having connection by means of arm-pipes 6^a and 6^b with the outlet-pipe 11 and inlet pipe 11^a, respectively, the pipe 11^a connecting at its upper end with the cylinder at the upper end, above the piston, the latter being provided with a valve similarly as the piston in Fig. 2, the valve 9 105 being arranged in the well-pipe intermediate the connections of the two arms 6^a and 6^b of the well-pipe 7. 110

It will be observed that, referring more particularly to the disclosure of Fig. 6, 115 wherein the device functions to take in the water into the upper end of the cylinder, the valve 9 of the well-pipe 7 is not functioning—should not function then—the outtake then being by way of the arm-pipe 6^a to the 120 outtake or service pipe 11, this obviously being necessary, otherwise the water would return or pass back through the pipe 7 into the well, the intake in this case being by way of the arm-pipe 6^b to the service 125 pipe 11.

It will be seen that by the above construction a water elevator has been provided which can be used in place of a hand-operated pump or a small gasoline engine, for 130

furnishing water in a private water system, for example; to and through a house, park, garage, lawn or wherever water is required.

The device operates as follows:

- 5 The weight 3 carrying the plunger is lifted by hand with the aid of any convenient mechanical device, such for example as the one illustrated in the drawings. Considering Fig. 1 when the weight is raised 10 the plunger being raised also, the inlet valve is opened and the water is drawn into the container 1. When the weight and plunger are allowed to fall by gravity, the outlet valve is opened and water is forced out of 15 the container 1 through the outlet valve and into the outlet pipe 11.

Referring to Fig. 2, when the weight and plunger are raised the inlet valve 9 is opened and water is drawn into the container 1. On 20 the downstroke of the piston the outlet valve 13 is opened and water is forced out of the container 1 and into the outlet pipe 11 to the point of distribution. Furthermore in the construction shown in Fig. 2, on the 25 downstroke of the piston a certain amount of water will be drawn into the container above the piston through the upper inlet valve 14^a; thus water flows in the space above the piston to occupy the increasing 30 volume as the piston moves down. When the piston moves up the upper inlet valve 14^a is automatically closed and the water that is above the piston is forced through the piston by means of the downwardly 35 opening valve 2^b provided in the piston.

The construction disclosed in Fig. 4 op-

erates in substantially the same way as the construction disclosed in Fig. 2, except that there is provided a double arrangement of parts.

40

The construction disclosed in Fig. 3 operates in a manner similar to that described in connection with Fig. 2 with this difference; in Fig. 3 the valves 15 and 9 are opened at the same time and closed at the 45 same time, and the valves 13 and 14^a are opened at the same time and closed at the same time. On the downstroke of the piston 2 water is forced out through the valve 13 and drawn in through the valve 14^a. On the 50 upstroke of the piston water is forced out through the valve 15 and drawn in through the valve 9.

I claim and desire to secure by Letters Patent:

55

A device of the type described, including a water-containing or receiving cylinder, a weighted valve-equipped piston arranged in said cylinder, the valve of said piston opening downwardly and delivering into the 60 cylinder as the piston performs its up-stroke for delivering the water from above the piston down into the cylinder, a valved intake delivering into the cylinder above the piston, a second valved intake delivering 65 into the cylinder below the piston and a valved ejection pipe connected with the cylinder at the lower end thereof, adapted to discharge the water entering the cylinder at a common point therefrom.

70

In testimony whereof I affix my signature,
VERNON J. MILLER.
